UNITED STATES PATENT OFFICE

JAMES HENRY REID, OF NEWARK, NEW JERSEY, ASSIGNOR TO INTERNATIONAL NITROGEN COMPANY, A CORPORATION OF DELAWARE.

PROCESS OF MAKING CALCIUM OR OTHER METAL NITROCARBID.

1,297,246.

Specification of Letters Patent.

Patented Mar. 11, 1919.

No Drawing.

Application filed June 28, 1915. Serial No. 36,659.

To all whom it may concern:

Be it known that I, JAMES HENRY REID, a citizen of the United States, residing at 352 Mulberry avenue, in the city of Newark, 5 county of Essex, State of New Jersey, have invented certain new and useful Improvements in Processes of Making Calcium or other Metal Nitrocarbid, of which the following is a specification.

10 This invention relates to the fixation of nitrogen and the making of metal nitro-carbids, such as cyanamids, and comprises combining nitrogen, while under super-atmospheric pressure, with metal and carbon by 15 exposing metal carbid to the action of nitrogen and heat, while under super-atmospheric pressure, in such a manner that the carbid is applied to the nitrogen at a temperature sufficient to elevate the nitrogen to 20 a point suitable for its combination or reaction and fixation while under pressure and particularly by introducing molten metal carbid, such as calcium carbid, into nitrogen which is under super-atmospheric pressure to the initial combining point, in 25 sure, and performing the fixation of the nitrogen upon cooling of the carbid to the combining point, with the simultaneous heating of the nitrogen while under pressure to the initial combining point, in 30 distinction to and from the prior art which reveals the supplying of heat and nitrogen to metal carbid to elevate the temperature up to a combining point or change it from a lower to a higher temperature 35 instead of from a higher to a lower temperature which constitutes one of the features of the present invention.

As an example of the process the making of calcium nitrocarbid, such as calcium 40 cyanamid, from calcium carbid by the action of nitrogen under pressure will be taken.

Calcium carbid in a molten state and preferably that which is freshly reduced and made or tapped from a furnace where 45 formed, is introduced into a suitable chamber containing nitrogen gas, which is preferably under a pressure of six atmospheres, and allowed to fall through the atmosphere of compressed nitrogen until the nitrogen 50 combined therewith through the cooling of the carbid and simultaneous heating of the nitrogen gas creating a temperature selective to the combination which results in the formation of calcium nitrocarbid, such as 55 cyanamid, and free carbon in accordance

with the following chemical reaction or equation:—

As the carbid seizes the nitrogen and fixes 60 the same, more nitrogen is supplied from time to time to compensate for that combined, provided any is required over that sufficient to satisfy the carbid in its conversion.

65 The heat necessary for the initiation or starting of the reaction is carried with the carbid and hence is more positive and controlled and of greater heating effect than in the prior art where heat from exterior combustion or other means is passed through a 70 retort or container to heat cold carbid which results not only necessarily in expense by loss in the production of combustion heat and through heat resistance of the retort but 75 also in difficulties experienced through the heat non-conductive carbid together with the surrounding heat non-conductive nitrogen which produces a heat condition almost impossible to control or regulate, thereby 80 increasing the difficulty in maintaining the ingredients within or at a temperature selective for complete or quick conversion of carbid into cyanamid or the fixation of nitrogen.

85 The heat liberated by the reaction and the heat conveyed to the nitrogen through the medium of molten carbid coact to facilitate the transformation of the carbid and fixation of the nitrogen which fixation progresses after the starting of the reaction and 90 adjusts the temperature with the production of product.

95 Any suitable carbid may be employed instead of calcium carbid and the carbid may be of simple, compound, composite or complex nature, such as double carbids of calcium and hydrogen, calcium and barium, etc., without departing from the spirit of the invention, so long as the molten carbid 100 is introduced in the nitrogen or nitrogen carrying yielding or delivering substance under super-atmospheric pressure.

105 The preferable carbid, such as calcium carbid, is that produced by direct combination or reaction of natural limestone or calcium carbonate with bituminous material, such as bituminous coal, at elevated temperatures preferably induced by electrical resistance, which results in a carbid which 110

melts and flows at a lower temperature than that ordinarily obtained because of its containing hydrogen in the combination or association which also facilitates the conversion into cyanamid in accordance with the following chemical formula or equation:—

This largely removes the carbon as a solid 10 contamination of the cyanamid product and renders the material more porous and thus facilitates the action of nitrogen on the carbid at the lower temperatures and with the more perfect result.

15 The reaction which results from the action of limestone or calcium carbonate on hydro-carbon, such as bituminous coal, in the formation of hydrogen-containing calcium carbid or what may be termed calcium hydro-20 carbid or calcium-ethylenid may be illustrated by the following chemical formula or equation:—

25 By subjecting metal carbid, such as calcium carbid, to the action of nitrogen under pressure, the carbid being introduced in a molten state and more perfect conversion of the carbid into nitro-carbid, such as cyanamid, is accomplished in less time and in a more perfect and controlled manner and at lower temperatures than under ordinary atmospheric pressure whereby a longer period or wider scope of temperature within which 35 nitrogen combines with the carbid results.

The nitrogen may be supplied from time to time to maintain the pressure and a sufficient supply of nitrogen to combine with the metal carbid desired to be transformed into 40 nitro-carbid or cyanamid.

The pressure is found to be preferably about six atmospheres when the conversion of calcium carbid into calcium nitro-carbid or cyanamid by the action of nitrogen is desired but any selective pressure may be employed in connection with the calcium carbid or other metal carbid or hydro-carbids desired without departing from the spirit of the invention.

50 Should the materials being transformed during the fixation of nitrogen become super-heated by reason of the increased pressure and heat isolation or insulation they may be cooled or refrigerated by the introduction of cool gases or other means to maintain the temperature suitable for the formation of the compound desired under the particular pressure employed.

The term or expression "super-atmospheric pressure" employed herein is intended to imply and does imply a pressure greater than that of atmospheric pressure

under normal conditions, viz.:—15 pounds to the square inch, and is not intended to limit the operation or process to any particular pressure which may differ according to the character of the material to which it is desired to fix nitrogen or the nature of the compound to be produced.

Having now described my invention what 70 I claim as new and desire to secure by Letters Patent is:—

1. The process of making metal nitro-carbid which comprises introducing a molten metal carbid into an atmosphere of nitrogen, which is under super-atmospheric pressure, and maintaining the association of the ingredients until nitrogen has combined therewith.

2. The process of making metal nitro-carbid, which comprises exposing a molten metal carbid to the action of nitrogen while under superatmospheric pressure.

3. The process of making metal nitro-carbid which comprises conveying heat to 85 a zone of reaction between metal carbid and nitrogen, while under super-atmospheric pressure, through the medium of molten or liquefied metal carbid.

4. The process of making metal nitro-carbid which comprises introducing a molten calcium-containing carbid into an atmosphere of nitrogen, which is under super-atmospheric pressure, and maintaining the association of the ingredients until nitro- 95 gen has combined therewith.

5. The process of making metal nitro-carbid, which comprises exposing molten calcium containing carbid to the action of nitrogen while under superatmospheric 100 pressure.

6. The process of making calcium nitro-carbid which comprises introducing molten calcium carbid into an atmosphere of nitrogen, which is under super-atmospheric pressure, and maintaining the association of the ingredients until nitrogen has combined therewith.

7. The process of making calcium nitro-carbid, which comprises exposing molten calcium carbid to the action of nitrogen while under superatmospheric pressure.

8. The process of making calcium nitro-carbid which comprises conveying heat to a zone of reaction between calcium carbid and 115 nitrogen, while under super-atmospheric pressure, through the medium of molten or liquefied metal carbid.

In testimony whereof I affix my signature in presence of two witnesses.

JAMES HENRY REID. [L. s.]

Witnesses:

F. L. WHITNER,
CHARLES WIESENBERG.
